ATHLETIC SHOE SOLE

Jeffrey O. Johnson, Exeter, N.H., assignor to BRS, Inc.,
Beaverton, Oreg.

Filed Apr. 28, 1975, Ser. No. 571,971

Term of patent 14 years

Int. Cl. D2—04

U.S. Cl. D2—320

FIG. 1

FIG. 2

FIG. 1 is a side elevation view of an athletic shoe employing the shoe sole of our new design, the upper portion of such shoe being shown in phantom lines and forming no part of such new design; and

FIG. 2 is a bottom elevation view of the shoe sole of FIG. 1.

The top view of the shoe sole is unornamented and forms no part of the new design, the other side view is substantially the same as FIG. 1, and the front and rear views are the same as the left and right end portions, respectively, of FIG. 1, so none of these views are shown.

I claim:

The ornamental design for an athletic shoe sole, as shown and described.
